ESCAPEMENT MECHANISM FOR
TYPEWRITERSGiuseppe Prezioso, Yverdon, Switzerland, assign-
or to E. Paillard et Cie S. A., Yverdon, Switzer-
land, a corporation of SwitzerlandApplication August 7, 1941, Serial No. 405,875
In Switzerland February 6, 1941

5 Claims. (Cl. 197—88)

Known escapement mechanisms for typewriting, adding and similar machines generally comprise a pinion which meshes with the rack fitted on the carriage, said pinion being secured to a shaft and actuating a ratchet wheel which cooperates with retaining and escapement pawls.

So far as strength, rapidity, accuracy, silence and touch safety are concerned, the present requirements are such that known escapement mechanisms cannot meet them all, and compromise solutions had to be adopted. Thus for example a very quick acting escapement mechanism is generally less silent and probably less accurate than an escapement mechanism allowing of a reduced touch speed.

A major disadvantage of known escapement mechanisms is that they comprise only one ratchet wheel on which the retaining pawl and the escapement pawl both act. Now the outline of a tooth of this ratchet wheel, adapted to cooperate with the retaining pawl, must fulfill requirements different from those of a tooth cooperating with the escapement pawl. In fact one tooth must be capable of stopping the carriage in a predetermined position, while the other tooth must hold the same momentarily in its position while the key is depressed.

When stresses on both pawls are small, they can operate on teeth having the same outline. However, for quite a number of years now, it has been customary practice to provide each tooth with two different engaging surfaces, the two pawls being then arranged on the opposite sides of the ratchet wheel and engaging the respective side faces of said wheel.

This construction made it possible to increase touch swiftness. As requirements regarding noiselessness have been growing more and more, attempts were made to render such mechanisms silent by the provision of elastic cushions or else by mounting both pawls on a floating block. However all the foregoing improvements rendered such mechanisms very complicated and weak in structure especially for large size machines which are employed for office work and consequently subjected to heavy duty and which consequently are not very accessible and very delicate in their adjustment without permitting a complete fulfillment of the above-cited requirements.

The present invention has for its primary object to provide an improved escapement mechanism for typewriting, adding and other similar machines, said mechanism being adapted to obviate the aforesaid disadvantages while satisfying all practical requirements and ensuring a great

operational simplification and proper touch safety over a wide range of typewriting speeds.

Another object of the invention is to provide an improved escapement mechanism for typewriting and similar machines the elements of which are so arranged as to provide proper clearance between them as well as easy accessibility.

Another object still of the invention is to provide an improved escapement mechanism for typewriters, comprising a pair of independently pivoted and guided pawls or dogs having differentiated functions and cooperating with a pair of ratchet wheels, the arrangement being such as to permit quick and easy adjustment and control of each pawl.

A further object of the invention is to provide an improved escapement mechanism whose cooperating members have surfaces specially adapted for avoiding rattle so that the general operation of the typewriter is substantially noiseless while the movement of the carriage remains quick and accurate.

Still a further object of the invention is to provide an improved escapement mechanism so built as to permit the grouping upon a unitary block frame of all the operating members for the escapement mechanism, the decimal tabulator, the means for positioning and withdrawing tabulator stops upon the carriage, the brake, the carriage free release, the paper carriage braked release, the carriage return, and means adapted to eliminate any rattle during the return movement of said carriage, means to provide a variable spacing, and means to control the escapement action by the space bar of the typewriter.

With these and such other objects in view as will appear hereafter, the invention comprises the novel construction, disposition and combination of elements that will now be described in detail with reference to the accompanying drawing showing by way of example in perspective a suitable constructional form of the improved escapement mechanism as applied to a typewriter.

In the sole figure forming a part of the present disclosure only those elements which are necessary for a proper understanding of the invention have been shown, the other known elements being obvious to those skilled in the art.

In the sole figure, reference character 1 designates a pinion adapted to come into meshing engagement with a rack of known form fitted on the machine carriage (not shown) which may have any conventional construction. The machine has the usual universal bar (not shown). The pinion 1 is secured to a stub shaft 2 to which

are rigidly fixed a pair of ratchet wheels 3, 4. The pinion 1 is secured to one end of the shaft 2, while the ratchet wheels are secured to its middle portion. The free end of the stub shaft 2 is pivoted in a bearing-like recess formed in an escapement frame 6.

In order to impart greater rigidity to the assembly and to properly hold the shaft 2 in vertical position, the frame 6 comprises a further bearing situated under the pinion 1.

The second ratchet wheel 4 has spur gearing and cooperates with a retaining pawl 8 pivoted on a stud 9 mounted on a member 10 slidably received in recesses 11 formed in the frame 6. The retaining pawl 8 is urged by a spring 12 fixed thereto at one end and attached at its other end to the sliding member 10. Said spring tends to push the retaining pawl 8 into engagement with the second ratchet wheel 4. The sliding member 10 is urged by a tension spring 5 in a direction to the right as viewed in the drawing. The stroke of the member 10 is limited by the fact that its end 13 urged by the spring 5 contacts pivoted stops 44, 45 or the face 51 of a block 85 on which are pivoted said stops. Swinging of stops 44, 45 into or out of the sliding path of sliding member 10 may be directly controlled, or controlled by the depression of a key or through a universal bar. The stops 44, 45 are held in the position as shown in the drawing by springs 44a, 45a, and are operated by traction rods 44b, 45b. The arrangement is such that the stop 44 can move independently by itself while the stop 45 can only move by carrying along with it the companion stop 44 through the medium of a lug 45c. In order to lessen rattle, the end face 13 of the sliding member 10 may be lined with a resilient or sound-absorbing substance.

The retaining pawl 8 is provided with an operating member which comprises a stud 14 adapted, when a key is depressed, to engage an arm 15 secured to an auxiliary shaft 16 arranged parallel to the sliding member 10. The auxiliary shaft 16 has rigidly fixed thereto the following members, namely: a roller 17 adapted to come into contact with the main universal bar of the type bars (not shown), a spacing finger 60 actuated by the space bar of the typewriter, and an escapement pawl constituted by a dog 18 adapted to engage the teeth of the first ratchet wheel 3. Obviously the roller 17 may be made of noiseless material. The dog 18 may also be fixed to the block 16a by means of securing members also made of noiseless material. The auxiliary shaft 16 is subjected to the torsional urging of a helical spring 19 the tendency of which is, on the one hand, to constantly hold the roller 17 in contact with the main universal bar and, on the other hand, to keep the dog 18 clear of the first ratchet wheel 3. The auxiliary shaft 16 pivots on adjustable headstocks 20 housed in suitable recesses of the frame 6.

The dog of the escapement pawl 18 is mounted on the block 16a through the intermediary of a piece of noise-reducing material 16b. The movement of the sliding member 10 is limited in one direction by a disk 13a of noise-reducing material fixed on its extremity and being supported on a fixed part, and limited in the other direction by a piece 13 of noise-reducing material covering its extremity and being supported on one of the stops, 44, 45, or the block 51.

A tongue 29 secured to a yoke-shaped piece 30

pivoted at 31 on the side faces of the frame 6 is actuated by a lever adapted to unlock the carriage (not shown) and acts through the medium of levers 32, 33, on the retaining pawl 8 against the action of the spring 12 to disengage the retaining pawl 8 from the second ratchet wheel 4. The lever 33 is pulled back to its position of rest by a spring 67.

The rear face of the frame 6 is provided with vertical grooves in which can slide members adapted to stop the decimal tabulator, said members comprising tongues 35 actuated in the upward direction by means of certain keys of the keyboard (not shown) and levers pivotally connected at 36. Each tongue 35 has a nose 40 adapted to engage and actuate a tabulator universal bar 37 having a yoke shape and pivoted on pintle 38 on both side faces of the frame 6. The tabulator universal bar 37 actuates the following members, namely:

(a) The retaining pawl 8 against the action of its return spring 12 by pressing the lever 33, thus freeing the carriage which is then quickly shifted under the influence of its return spring;

(b) A brake constituted by a pair of shoes 41 which clamp between them a stub shaft 42 secured to a toothed wheel 34. The operation of this brake is effected under the control of the tabulator universal bar 37 by bringing the toothed wheel 34 into engagement with an annular gear 39 secured to the shaft 2. A return spring 69 urges the brake-carrier 70 into contact with a portion of the tabulator universal bar 37.

On the one end of the pin 38 is rigidly mounted an operating lever 80 by which the tabulator universal bar 31 is operated when a key of the keyboard is depressed so as to release the carriage (by bringing the brake into action) independently of the operative positioned tabulator stops.

Obviously the control of these several members by the tabulator universal bar 31 may be arranged to suit requirements in a way different from the one described. For example the brake may be controlled through the medium of the spring 69 with a view to facilitating adjustments.

The rear face of the frame 6 is provided, moreover with controls for proper positioning and spacing of these stops which are supported by the carriage and are adapted to engage with the tongues 35 of the decimal tabulator. The control for positioning the stops is performed by means of a finger-shaped member 46 pivoted at 81 and actuated by a special key of the keyboard through a bar (not shown) pivotally connected at 47. The finger 46 pushes the stop in front of which it is into operative position. The control of the withdrawal of the stops is ensured by a stud 48 also pivoted at 81 and adapted to bring back the stops to their inoperative position. The stud 48 is actuated from a key of the keyboard through the medium of a bar (not shown) pivotally connected at 82.

In order to obviate the rattle of the escapement pawl 8 as it rubs the teeth of second ratchet wheel 4 during the return stroke of the carriage, a groove 54 is formed in said ratchet wheel 4. In said groove is received a wire ring member 55 elastically clamped against its bottom. One end 56 of this ring member is radially bent outwardly. When the stub shaft 2 rotates clockwise, i. e. in the direction of normal paper feed 75 of the carriage, the end 56 of the ring member

55 is frictionally driven and abuts a stud 51 on the frame 6. However, when the shaft 2 rotates counter-clockwise, i. e. during the return stroke of the carriage, said end 56 of the ring member 55 comes into engagement with a ramp 72 formed on the pawl 8 and holds it out of contact with the second ratchet wheel during the return stroke of the carriage, thus avoiding rattle from the pawl contacting the teeth of the second ratchet wheel.

The frame 6 is preferably constituted by a block structure formed with the necessary recesses for accommodating the several members mounted thereon and enumerated in the foregoing description. Said block has a wide surface 50 formed with bores for the securing members 49. Between the base surface of the block 6 and that formed on the machine frame 63 for receiving the same and also between the securing members and the block 6 are interposed elastic lining plates 61 (made for example of india rubber) the purpose of which is to avoid rattle while at the same time ensuring perfect steadiness of the block or frame 6 on the machine frame 63.

As will be easily understood, the operation of this improved escapement mechanism is substantially similar to that of an escapement mechanism of known construction. However, it presents very important advantages over the latter. Actually although at first sight it might appear that an escapement mechanism built according to the present invention has a more intricate structure than an escapement mechanism of known type merely comprising a single ratchet wheel cooperating with a pair of pawls, the present invention involves in fact a great operational simplification.

Owing to the fact that there are provided two ratchet wheels, one cooperating with the escapement pawl, and another one cooperating with the retaining pawl, each set of teeth may be so shaped as to conform to the operation of the pawls. Thus no compromise need be resorted to, as is the case when there is only one ratchet wheel, for providing outlines ensuring a sufficient touch safety for any given writing speed.

As illustrated, the set of teeth of the ratchet wheel cooperating with the escapement pawl has a slanting outline so as to facilitate the release of the pawl which should retain the carriage momentarily only while the type bar is being struck. However, the teeth of the set cooperating with the retaining pawl have radial and vertical faces on which the pawl cannot slide.

Furthermore, owing to the provision of a pair of ratchet wheels, the orientation of said wheels and of the pawls cooperating therewith may be selected at will. In other words, it is then possible so to arrange the elements as to provide a proper clearance between them as well as an easy accessibility.

Each pawl is pivoted and guided independently of the other pawl, which permits to give them a rugged construction while allowing of an extraordinary rapid and easy adjustment. Moreover, as each pawl has proper clearance and accessibility, its control is very easy and can be achieved for example by means of a mere push rod. This obviates intricate and long mounting or assembling operations.

Moreover, as each pawl and the ratchet wheels may be oriented at will, such members may be so arranged as to provide sufficient clearance for lining the abutments with sound-absorbing material and providing them with wide contact sur-

faces. This absorbs the shocks and provides a noiseless escapement without interfering with the rapidity and accuracy of the type bar stroke. The several members and particularly the pawls may be so arranged as to constitute a rugged frame. It thus becomes possible owing to the present invention to provide a strong, accurate, rapid and noiseless escapement mechanism even for typewriters or similar machines comprising the heaviest type of carriage which are in existence.

As, moreover, each pawl is independently pivoted, it can be operated for itself. It thus becomes possible to release the retaining pawl without engaging the escapement pawl and to free the carriage in that way.

During the type bar stroke, the pawl 8 engages the following tooth corresponding to the stop 44 or the second tooth corresponding to the stop 45 or, alternatively, the third tooth corresponding to the block face 51. This permits manually to modify at will either by means of a key or automatically by means of one or several universal bars the space between the types, and to provide it single, double or treble. This involves a particular advantage when typewriting must be effected with types having different widths as is the case with gothic, arabic or other special types, also for typewriting titles, subtitles, addresses, captions etc. in which the intertype spaces must be larger than the normal space size.

The reciprocatory motion of the retaining pawl rod is preferably tangential to the second ratchet wheel 4. This motion permits the elimination of the noise due to the impact of the carriage against this pawl. This is due to the fact that whenever the pawl 8 is disengaged, it comes into engagement with the following tooth during the type bar stroke. Consequently the impact instead of taking place between the tooth and the pawl takes place between the abutment 13 and the face of the frame 6. Said abutment may be made wide enough to prevent rattle.

It will be understood that the constructional details of an escapement mechanism according to the invention may be different from those described. Thus the bearings for the shaft 2 may be provided with balls or rollers, and the several members may be arranged on the frame 6 and shaped to suit requirements and to fit the particular type of machine to which the mechanism is adaptable.

The other constructional details may also vary without departing from the scope of the subjoined claims.

What is claimed is:

1. In an escapement unit, a frame, a pinion shaft rotatably mounted on said frame, a driven pinion keyed on said shaft, an escapement ratchet wheel having teeth with edges oblique to the radius thereof, a retaining ratchet wheel having teeth with edges substantially radial, and an escapement pawl and a retaining pawl mounted independently on individual pivots and adapted to respectively engage said teeth of said ratchet wheels, said pawls being so arranged and operated that said escapement pawl normally engages said escapement ratchet wheel before said retaining pawl is released from said retaining ratchet wheel.

2. In an escapement unit, a frame, a pinion shaft rotatably mounted on said frame, a driven pinion keyed on said shaft, an escapement ratchet wheel having teeth with edges oblique to the radius thereof, a retaining ratchet wheel having teeth

with edges substantially radial, a slide member slidably mounted on said frame, a retaining pawl pivotally mounted on said slide member, and an escapement pawl pivotally mounted independently of said retaining pawl, said pawls being adapted to respectively engage said teeth of said ratchet wheels, said pawls being so arranged and operated that said escapement pawl normally engages said escapement ratchet wheel before said retaining pawl is released from said retaining ratchet wheel.

3. In an escapement unit, a frame, a pinion shaft rotatably mounted on said frame, a driven pinion keyed on said shaft, an escapement ratchet wheel having teeth with edges oblique to the radius thereof, a retaining ratchet wheel having teeth with edges substantially radial, a slide member slidably mounted on said frame, a retaining pawl pivotally mounted on said slide member, an escapement pawl pivotally mounted independently of said retaining pawl, said pawls being adapted to respectively engage said teeth of said ratchet wheels, said pawls being so arranged and operated that said escapement pawl normally engages said escapement ratchet wheel before said retaining pawl is released from said retaining ratchet wheel, and a plurality of stop members selectively insertable in the path of travel of said slide member for controllably adjusting the maximum travel thereof.

4. In an escapement unit, a frame, a pinion shaft rotatably mounted on said frame, a driven pinion keyed on said shaft, an escapement ratchet

wheel having teeth with edges oblique to the radius thereof, a retaining ratchet wheel having teeth with edges substantially radial, a slide member slidably mounted on said frame, a retaining pawl pivotally mounted on said slide member, an escapement pawl pivotally mounted independently of said retaining pawl, said pawls being adapted to respectively engage said teeth of said ratchet wheels, said pawls being so arranged and operated that said escapement pawl normal engages said escapement ratchet wheel before said retaining pawl is released from said retaining ratchet wheel, and an auxiliary shaft rotatably mounted parallel to said slide member and carrying means pivotally carrying said escapement pawl.

5. In an escapement unit, a frame, a pinion shaft rotatably mounted on said frame, a driven pinion keyed on said shaft, an escapement ratchet wheel having teeth with edges oblique to the radius thereof, a retaining ratchet wheel having teeth with edges substantially radial, a slide member slidably mounted on said frame, a retaining pawl pivotally mounted on said slide member, an escapement pawl pivotally mounted independently of said retaining pawl, said pawls being adapted to respectively engage said teeth of said ratchet wheels, and an auxiliary shaft rotatably mounted parallel to said slide member and carrying means pivotally carrying said escapement pawl, said pinion shaft, said auxiliary shaft, and the pivot which mounts said retaining pawl on said slide, all three being mutually perpendicular.

GIUSEPPE PREZIOSO.
